UNITED STATES PATENT OFFICE.

JAMES H. PREATER, OF BROOKLYN, NEW YORK.

BAG FOR PACKING AND STORING.

SPECIFICATION forming part of Letters Patent No. 229,333, dated June 29, 1880.

Application filed May 3, 1880. (No model.)

To all whom it may concern:

Be it known that I, JAMES H. PREATER, of Brooklyn, in the county of Kings and State of New York, have invented an Improvement 5 in Bags for Packing and Storing Coffee, Grains, Seeds, or other Articles, of which the following is a specification.

Bags have been made of canvas, cloth, gunny, and similar materials. They are inconvenient in handling, the contents are liable to become injured if the bag is allowed to remain on a wet or dirty place, and the opening and closing of the bag are attended with difficulty, and if the bag is opened to display the 15 contents it may tip over and spill the material out.

My improvement is made to overcome all these difficulties; and it consists in a cylinder of canvas or similar material secured at the 20 ends to hoops in combination with rigid heads to which the hoops and canvas cylinder are connected. One head is removable, so that the contents of the bag can be examined, or a portion or the whole removed or emptied out. 25 This construction allows for the bag to be rolled from place to place, the bag and contents are protected from injury by the wooden head when resting upon the earth or upon any damp or dirty place, and the bag will stand 30 up firmly without the risk of falling over, and the head can be removed, and the bag can be pushed down as the contents are removed, so as to give access to such contents and to allow them to be inspected.

35 In the drawings, Figure 1 is a vertical section of the bag complete, and Fig. 2 is a side view of the same with the lid removed and the flexible cylinder pushed down to show the contents.

The cylinder *a* is of gunny-cloth, canvas, or 40 other suitable material. It is made up in the form of a cylinder, with the ends turned over to inclose a hoop, *b*, which by preference is used at both ends, but may only be used at the end where there is a removable head, *c*. The bottom *d* and head *c* are both made with an offset 45 or shoulder at 2, to allow for the attachment of the canvas cylinder *a* by nails or screws, and so that the projecting portions of the periphery of each head will serve as a protection 50 for the canvas and as a convenience in handling the package.

The hoop *b* should be used at both ends of the cylinder, the cloth being wrapped around the same so as to be firmly secured; but at the 55 bottom the same may be dispensed with if the canvas is nailed directly to the edges of the head.

The hoop at the upper end of the canvas cylinder supports the same and keeps it in 60 the proper shape when the package is open for the inspection of the contents.

It is preferable to attach the hook to the movable head by ordinary wood-screws.

I claim as my invention— 65
The combination, in a package for merchandise, of a cylinder of canvas, cloth, gunny, or similar material, a hoop around which the cloth at one end is secured, and two circular heads of wood or similar material, substantially as set forth.

Signed by me this 30th day of April, A. D. 1880:

JAMES H. PREATER.
